Patented Apr. 27, 1915.

UNITED STATES PATENT OFFICE.

WILLIS S. SHERMAN, OF MILWAUKEE, WISCONSIN.

CARBURETER.

1,137,238.

Specification of Letters Patent. Patented Apr. 27, 1915.

Application filed April 18, 1913. Serial No. 761,897.

To all whom it may concern:

Be it known that I, WILLIS S. SHERMAN, a citizen of the United States, and resident of Milwaukee, in the county of Milwaukee and State of Wisconsin, have invented new and useful Improvements in Carbureters, of which the following is a description, reference being had to the accompanying drawings, which are a part of this specification.

This invention relates to carbureters and has for its object to provide a carbureter adapted for use with low or high test liquid fuels by having a rotating element impelled by the suction from a gas engine and adapted by its rotary motion to act upon the flow of liquid fuel in such a manner as to spread the liquid fuel into a thin film and discharge it by centrifugal action at its edges into the current of air on its way to the gas engine and thus effect a uniform and complete mixture of liquid fuel and air.

Another object of the invention is to perfect details of construction of a carbureter of this character.

With the above and other objects in view the invention consists in the carbureter as herein claimed and all equivalents.

Referring to the accompanying drawings in which like characters of reference indicate the same parts in different views: Figure 1 is a central vertical sectional view of a carbureter constructed in accordance with this invention; Fig. 2 is a sectional plan view thereof on the plane of line 2—2 of Fig. 1; Fig. 3 is a detail edge view of the rotary member; Fig. 4 is a bottom view of the convex plate; Fig. 5 is a plan view of the float; Fig. 6 is a sectional view on the plane of line 6—6 of Fig. 1; and, Fig. 7 is a sectional view on the plane of line 7—7 of Fig. 1.

In these drawings the carbureter is shown to be contained within a casing comprising a bell shaped upper part 10 adapted for connection with the intake of a gas engine or the like and a ring shaped lower part 11 coaxial with the upper part and connected with it by a number of spacing arms 12 which form rigid connections between the parts of the casing but hold them spaced apart.

The upper portion 10 of the casing has an ordinary throttle valve 13 in the passage-way leading from it to the intake of the engine.

Both the upper and the lower portions of

the casing are internally threaded and an adjusting ring 14 with an inturned flange 15 at its upper edge is threaded in the upper portion 10 of the casing while a cup-shaped float chamber 16 with a contracted waste portion is threaded into the ring portion 11 of the casing. The float chamber contains a central opening in its bottom in which a plug 17 fits and this plug has a suitable pipe connection 18 with the source of supply of gasoline under pressure. A conical valve 19 is adapted to be seated against the lower end of the opening through the plug 17 and its square valve stem 20 fits within said opening to guide the valve in its movements without interfering with the passage of gasoline through the opening and on the upper end of the valve stem is threaded a square nut 21 fitting within a square opening in metal cross arms 22 which are attached to an annular float member 23. The float chamber has a tubular projection 24 standing upright therein around its bottom opening and this tubular projection is slotted radially to receive the cross arms 22 as seen in Figs. 1 and 5. The square nut 21 is provided with flanges engaging above and below the cross arms 22 so that the movements of the float are imparted to the valve stem and the inflow of gasoline is controlled by the closing of the valve when the predetermined level of gasoline in the float chamber is reached. The valve 19 is provided with a square head 25 which fits in a correspondingly shaped portion of the opening of plug 17 to normally prevent the turning of the valve stem, but below the square portion of the opening of plug 17 there is a rounded portion which permits the square head 25 to turn and when it is desired to vary the level of gasoline in the float chamber permitted by the float it is only necessary to engage a screw driver in a slot at the upper end of the valve stem 20 and by depressing the float until the square head 25 is in the rounded portion of the opening of plug 17 the turning of the valve stem within the square nut will vary the distance between the float and the valve to correspondingly vary the gasoline level in the float chamber.

The upper portion 10 of the casing has a number of radial arms 26 supporting centrally within it a flanged bearing seat 27 in which is fitted an outer bearing ring 28 of a ball bearing 29, the inner bearing ring

30 thereof having a bolt 31 passed therethrough and clamping it to a rotary member 32 which is a disk, saucer like or concave in shape, and has a convex member 33 between it and the inner bearing. The convex 5 surface of the convex member 33 and the concave surface of the rotary member 32 are slightly spaced apart by means of short radial ribs 34 on the bottom of the convex 10 member 33 and gasoline is supplied to the space between the concave and the convex members from radial openings in the bolt 31 which communicate with a central opening in the bolt with its lower end submerged 15 beneath the gasoline level in the float chamber.

To restrict the flow of gasoline to the rotary member there is a plug 35 threaded in the lower end of the central opening of the bolt 31 and having a very fine opening leading through it and preferably terminating in an annular groove around the upper end of the plug which communicates with the space above the plug through small openings, thus breaking up the force of the jet of gasoline due to its passage through the small opening of the plug under the strong action of the suction from the engine and thus permitting the gasoline to flow freely 30 out through the openings of the bolt 31 to the space between the concave member 32 and the convex member 33. The bolt 31 by clamping the inner ring 30 of the ball bearing and the convex member 33 to the rotary 35 member 32 binds these parts together so that they move as one and are supported by the ball bearing so as to be free to turn therein. The rotary member 32 is provided with inclined radial ribs or wings 36 which extend 40 across the space between the rotary member and the adjusting ring 14 and the flow of air through this space caused by the suction from the engine acts upon these inclined wings 36 to propel the rotary member and 45 cause it to spin rapidly.

The suction from the engine causes the gasoline or other liquid fuel to rise through the opening in the plug 35 and pass through the openings of the bolt 31 to the space between the concave rotary member 32 and the convex member 33 where, by reason of the rapid rotary motion of the rotary member, it is carried by centrifugal action up the inclined walls of the rotary member toward 50 the edge thereof, becoming drawn out more and more as it covers the greater area of surface until reaching the edge of the rotary member as a thin film. At the edge of the rotary member the fuel is thrown off by 55 centrifugal action across the current of incoming air between the rotary member and the adjusting ring 14 with which it readily mixes because of its finely divided state to form the explosive mixture.

60 85. In order to vary the proportions of air

and gas in the mixture the adjusting ring 14 may be turned to raise or lower its in-turned flange 15 with relation to the edge of the rotary member so as to vary the sectional area of the air passageway around the rotary member.

A convenient means for turning the adjusting ring 14 consists of a split ring 37 which is threaded on the lower end of the adjusting ring 14 and after being adjustably positioned it is clamped firmly thereto by means of a set screw 38 passing through its ends.

The bearing seat 27 is provided with a cover 39 which limits the upward movement 80 of the bearing ring 28, for during the operation of the engine the rotary member is lifted off of its seat at the edge of the float chamber and the upper end of the tubular projection 24 so as to be entirely free to 85 spin under the influence of the suction without a bearing other than the ball bearing. When, however, there is an explosion in the carburetor, as is sometimes the case, the seating of the rotary member at the edges 90 of the float chamber and on the upper end of the tubular projection 24 effectively prevents its displacement without subjecting it to strain. Lubricant may be admitted to the ball bearing through an oil passageway 40 95 in one of the radial arms 26. In order that there may not be a discharge of liquid fuel through the space between the rotary member and the float chamber due to its creeping up the underside of the rotary member, an 100 annular rib 41 is formed on the bottom of the rotary member to throw off the liquid fuel which may be creeping up the bottom of the rotary member and an in-turned flange 42 is formed at the edge of the float 105 chamber to prevent the liquid fuel thus thrown off reaching the upper edge of the float chamber.

While this carburetor may be used with gasoline or other high test hydrocarbon, it 110 is particularly suitable for use with kerosene and other low grade hydrocarbons, for the principle involved of stretching fuel into a thin film and drawing it finer and finer until discharging it with force across a swiftly 115 moving current of air is found to produce an efficient vaporization with the latter without the necessity for the use of heat.

The invention is not confined to the particular details of construction shown and described as exemplifying the same but is capable of embodiment in various forms which will readily suggest themselves to one skilled in the art.

The concave or dish shape given to the rotary member requires the fuel to ascend in its outward travel and more surely spread over the surface of the rotary member without leaving it until reduced to a thin film which will be thrown by centrifugal action 130

as a thin spray across the surrounding current of air. Incidentally this concave shape of the rotary member may result in eddying currents of air above it having the same direction of travel as the fuel and tending to lick up the fuel before it reaches the edge of the disk.

Any form of float valve may be employed, but that shown is considered desirable and 10 while the removable plug 35 may take the form of a needle valve in order to be adjustable, it is sufficient to illustrate it in its present form whereby adjustment may be accomplished by substitution.

15 What I claim as new and desire to secure by Letters Patent is:

1. The combination in a carbureter of an air conduit adapted to have a current of air pass therethrough, of a suitably driven 20 rotary member mounted within the air conduit, said rotary member being disk shaped and concave or dished so that its edges incline toward the direction of travel of the current of air, and means for supplying 25 liquid fuel at the center of the rotary member to be drawn into a progressively thinner film as it moves over the surface of the rotary member toward the edges thereof by centrifugal action until forcibly discharged 30 from the edges of the rotary member across the current of air through the air conduit.

2. The combination in a carbureter, of a casing forming an air conduit adapted for connection with the intake of a gas engine 35 to create a current of air therethrough, a rotary member suitably mounted within the air conduit and receiving motion from the current of air, a flanged ring adjustably mounted in the casing for varying the area 40 of the passageway for the air around the rotary member, and means for supplying liquid fuel to the center of the rotary member to be forced by centrifugal action over the surface thereof into a progressively 45 thinner film until discharged from the edge of the rotary member into the current of air.

3. In a carbureter, the combination of a casing forming an air conduit adapted for 50 connection with the intake of a gas engine to have a current of air pass therethrough, an adjustable flanged ring threaded within

the casing, a rotary member suitably mounted within the casing and rotated by the current of air therethrough, a split ring threaded 55 on the flanged ring by which it may be adjusted to vary the area of the air passageway between it and the rotary member, and means for supplying liquid fuel to the center of the rotary member to be forced by centrifugal action over the surface thereof into a progressively thinner film until discharged 60 from the edge of the rotary member into the current of air.

4. The combination in a carbureter, of an 65 air conduit adapted to have a current of air pass therethrough, a rotary member suitably driven and mounted within the air conduit and comprising a concave disk with a convex disk fitting therein and spaced therefrom to 70 form a passageway between them, and means for supplying liquid fuel to the space between the concave disk and the convex disk to be forced by centrifugal action over the surface of the concave disk until discharged 75 from the edge thereof into the current of air.

5. The combination in a carbureter, of a casing forming an air conduit adapted to be attached to the intake of a gas engine to 80 have a current of air pass therethrough, a bearing seat supported by the casing within the air conduit, a ball bearing therein, a suitably driven rotary member journaled within the ball bearing and having a slight 85 endwise movement therein, a float chamber mounted on the casing beneath the rotary member and having the rotary member seated thereon in its lower position, a float controlled valve for controlling the admission 90 of liquid fuel to the float chamber, and means on the rotary member for delivering liquid fuel from the float chamber to the center of the rotary member to be forced by centrifugal action over the surface thereof 95 into a progressively thinner film until discharged from the edge thereof into the current of air.

In testimony whereof, I affix my signature, in presence of two witnesses.

WILLIS S. SHERMAN.
